DESIGN FOR A REFRIGERATOR

Application filed February 6, 1933. Serial No. 47,115. Term of patent 7 years.

To all whom it may concern:

Be it known that I, ROBERT T. FRAZIER, a citizen of the United States, residing at Chattanooga, county of Hamilton, State of Tennessee, and whose post office address is c/o Tennessee Furniture Corporation, in said city, have invented a new, original, and ornamental Design for a Refrigerator, of which the following is a specification, reference being had to the accompanying drawing, constituting a part thereof.

In the drawing:—

Fig. 1 is a front perspective view of a refrigerator showing my new design.

Fig. 2 is a section on the line 2—2, Fig. 1. The distinctive feature of the refrigerator resides in the fact that the edges of the top and sides of the casing, and the edges of the doors are round and are embossed as indicated more particularly in Fig. 2.

I claim:

The ornamental design for a refrigerator, substantially as shown and described.

In testimony whereof I have hereunto subscribed my name this 3rd day of February, 1933.

ROBERT T. FRAZIER.
